UNITED STATES PATENT OFFICE.

CHARLES D. McDONALD, OF LOS ANGELES, CALIFORNIA.

COMBINED TABLE, BED, AND BACK REST.

Application filed October 26, 1922. Serial No. 597,094.

To all whom it may concern:

Be it known that I, CHARLES D. McDONALD, a citizen of the United States, residing at Los Angeles, in the county of Los Angeles and State of California, have invented new and useful Improvements in Combined Tables, Beds, and Back Rests, of which the following is a specification.

This invention relates to a combined table, bed and back rest, and has for its object to provide a collapsible article which may be readily arranged to assume various forms at will. Another object is to provide a device consisting of a number of substantial frame elements capable of being assembled rigidly so as to form either a table frame, a bed frame, or a back rest. Another object is to provide a table top adapted to be readily applied to the erected frame. Another object is to provide a novel construction of supporting means for a mattress and bedding.

Other objects and advantages will be made manifest in the following specification of an embodiment of the invention illustrated in the accompanying drawings, wherein—

Figure 1 is a perspective view of the device erected to serve as a table;

Figure 2 is a perspective of the device arranged to serve as an elongated back rest for two or more people;

Figure 3 is a side view of the device erected so as to serve as an elongated back for the support of one individual;

Figure 4 is a cross section through one of the side bars showing the mattress supporting means attached thereto;

Figure 5 is a sectional detail transversely along a portion of the bed straps;

Figure 6 is a plan and sectional detail of one of the corner plates;

Figure 7 is a plan of a corner hinge in the frame forming position;

Figure 8 is a plan showing the action of the hinge of the frame pieces;

Figure 9 is a side elevation of one of the legs showing the hook attachment;

Figure 10 is an edge view of a leg showing the hook guide.

Figure 11 is a sectional view of the table top structure.

The embodiment of the invention here shown includes a suitable number of legs 2, the upper ends of which are hingedly connected at 3 in pairs to respective side rails 4 under and along which the several legs 2

are adapted to be folded, as clearly shown in Figure 2. When the legs are in the perpendicular or unfolded position, their ends abut against the contiguous faces of the side rails 4. The legs 2 are provided with elongated loop-like guide wires 5 positioned to receive the hooks 6 of brace wires 7 whose opposite ends are rigidly connected at 8 to the medial portions of their respective side rails 4. The hook wire 6 is adapted to be disconnected from the guides 5 to permit the folding of the legs 2 and is adapted to interlock with the guides 5, as shown in Figure 9, to hold the legs in erected position; the wire 7 also holding the legs folded.

Between their top and bottom faces the ends of the side rails 4 are slotted at 11 to receive hinge plates 12 through which pass pivot pins 13 in the ends of the side rails 4. A feature of the invention is that certain of the hinge plates 12 are slotted as at 12' to shift on the pivot pins 13 and thus allow the plates to swing around the ends of the side rails. The hinge plates 12 are secured by pins 14 to the contiguous end of an end bar 15 forming with the side rails 4 a bed or table frame in the erected position.

At the other ends of the cross bars 15 there are provided plates 12' fastened thereto by pivot pins 14', these plates being provided so that they may be entirely withdrawn from connection with the contiguous ends of the adjacent side rail 4.

A feature of the invention consists of the construction of a mattress supporting means designed to give a desired degree of flexibility. This mattress supporting means is here shown as including a set of parallel spring rods 16, one of which is supported along each side rail in a plurality of screw eyes 17 projecting inwardly, the screw eyes being alternately offset along the respective parallel side rails 4. Extending transversely from rail to rail is a number of parallel flexible webs or straps, such, for instance, as woven hemp straps 18, the ends of which are hemmed, and through the hems extend the spring rods 16. As clearly shown in Figure 2, one end of each hemp strap 18 straddles one of the rod supporting eyes 17 while the opposite end is spaced between the adjacent pair of supporting eyes. The transverse support forming straps 18 are thus yieldingly connected to the rails 4 and provide a yielding and comfortable mattress receiving means. Along the under-

neath of the basal portions of the straps 18 and along their marginal portions extend flexible straps, as of tape 20, which connect the straps 18 and prevent their undue lateral separation.

The structure may be readily converted into a table-like device when it has been erected by the application to the top of the frame 4-15 of a table top forming means.

10 This means is shown as comprising a stout sheet of material such, for instance, as canvas, indicated at 21, and longitudinally of the sheet of canvas extend upper and lower slats 22 and 23, respectively, which are shown in Figure 11 as being set in opposed symmetrical relation and fastened through and through, as by rivets 24. The slats 22 and the slats 23 are separated sufficiently at their parallel edges to provide for the rolling of the table top into a small compact form for storage and packing. The unrolled table top device is adapted to be arranged upon the top of the erected frame, as is clearly shown in Figure 1.

25 The foldable structure is capable of being utilized, as will be seen from the above description, either as an ordinary bed or cot, when the parts are assembled and braced, or the erected device may be covered by the table top to form a table. It is also possible to use the structure as a comfortable back rest for a number of individuals, this being made possible by folding the corner legs of one of the side rails 4 up under the rail, as shown in Figure 2, and extending and bracing the opposite legs and then placing the frame with one of its side rails down toward the ground and using the folded out legs as props to support the frame 40 in an inclined position resting on a longitudinal edge, the length of the frame providing for the comfortable support of a number of individuals.

45 In case a single individual should desire to use the structure as an inclined rest, the corner legs adjacent to one end of the frame are folded in as shown in Figure 3, while the legs at the other end of the frame are erected and braced and then the lower end 50 of the frame can be disposed on the ground or other primary support, the legs at the opposite end of the frame holding the latter in an upwardly inclined position lengthwise. Attached to the outer faces of the 55 legs 2, which fold when erected into the plane of the outer face of respective cross bars 15, are foldable brace and link members 25, these being pivotally connected as at 26 to respective legs and having at their 60 swinging ends hook portions adapted to be slipped into sockets 27 provided therefor in the outer faces of the cross bars 15.

My combined table, bed and back rest is

made having diagonally opposite corners of the same construction. For instance, the 65 extreme left hand corner as shown in Fig. 1, may be designated by the letter A and the diagonally opposite corner by the letter A', which it is presumed are made with a corner similar to that shown in Fig. 6. The other 70 two diagonal corners designated in a clockwise direction B and B' would be of the construction shown in Fig. 8. Therefore reading in a clockwise direction from the extreme left hand corner in Fig. 1, the corner A would be of the detachable kind shown in Fig. 6, the corner B of the extensible folding type of Fig. 8, the corner A' of the detachable type shown in Fig. 6 and the near corner B' formed according to Fig. 8 of 75 80 the extensible type. Therefore, in folding the table or bed the diagonal corners A and A' would be disconnected and the end bar 15 would be swivelled outwardly into alignment with its connected side bar 4 in the 85 manner illustrated in Fig. 8, until the end bar and side rail 4 will be in alignment for the opposite ends of the bed, the legs 2 having been previously folded as above described. Therefore in effect, applicant's 90 bed when folded comprises two long bars each the length of the side rails 4, plus the end bar 15, with the fabric of the bed connecting with bars and which may be utilized to roll them into a neat and compact bundle. 95 Further embodiments, modifications and variations may be resorted to within the spirit of the invention as here claimed.

What is claimed is:

1. In a combined table bed and back rest, 100 a pair of side rails, legs pivotally connected to the under face of said side rails, adjacent their ends, adapted to be folded into abutment with the side rails and into perpendicular positions, brace means for holding the 105 legs in perpendicular positions, cross bars connected to the opposite side rails at the opposite ends of the bed, said connection comprising a horizontal slot in the side rails, a hinge plate secured to the one end of the 110 cross bars, there being also a vertical pin and slot connection between the hinge plate and the side rail to allow the cross bars to hinge into longitudinal alignment with the side rails, the other end of each side rail being 115 connected to the other end of each cross bar by means of a disconnectible joint.

2. In a combined table bed and back rest as claimed in claim 1, in which the detachable connection comprises plates secured to 120 the cross bars and attached to the side rail by a pair of removable pins.

In testimony whereof I have signed my name to this specification.

CHARLES D. McDONALD.
